VAPOR SEAL

Frederick A. Dodelin, Glen Ridge, N. J., assignor
to Pyrene Development Corporation, Newark,
N. J., a corporation of Delaware

Application June 11, 1946, Serial No. 676,068

9 Claims. (Cl. 169—4)

1

This invention relates to fire prevention apparatus associated with a tank containing an inflammable material, such as gasoline, fuel oil, oil or the like.

Many proposals have been made for mounting foam producing equipment on or near a tank used for storing gasoline or other inflammable liquids, so that in case of fire in the tank, means is readily available to bring the blaze quickly under control. It has been recognized that such an installation should provide a seal which acts under normal conditions to prevent the escape of fumes or vapors of the inflammable liquid, not only to cut down shrinkage of the liquid during storage, but also to prevent such escaping fumes from becoming an extra fire hazard. At the same time, the means for preventing escape of these fumes should not interfere with the proper operation of the fire fighting equipment when it is needed.

Devices have been proposed utilizing foam producing equipment which communicates by a conduit with the tank and which includes in the conduit a sealing diaphragm normally used to prevent escape of vapors and intended to be broken by the pressure of foam or other fire extinguishing liquid forced through the conduit in case it is necessary to extinguish a fire.

Such apparatus has several disadvantages, amongst which is the difficulty of providing a diaphragm that is sufficiently strong to prevent escape of vapors and that is still sufficiently weak to be ruptured under the pressure of foam or other fire extinguishing liquid flowing through the conduit. If the diaphragm is made too weak, it is apt to be broken prematurely, allowing gasoline or other vapors to escape from the tank. On the other hand, if the diaphragm is made strong enough to resist any internal pressure developed inside the tank, one cannot be certain that it will be ruptured in case of a fire and permit the proper functioning of the fire extinguishing equipment. Furthermore, such a diaphragm when ruptured may be broken only at one or two points and thus seriously impede the flow of fire extinguishing fluid into the tank.

An object of my invention is to provide a vapor seal which acts positively to prevent the escape of vapors from a tank and that is always positively removed as a seal by the impact of a stream of fire extinguishing fluid delivered to the tank.

A further object of my invention is to provide a seal in the nature of a disc, held in place simply by gravity, to act as a check valve to prevent the escape of vapors from a tank and that may be readily lifted from the valve seat under the

2

velocity or impact of fire extinguishing fluid to clear the passage for unobstructed delivery of the fluid to the tank in case of fire.

Other objects and advantages of the invention will be apparent and will be explained in connection with the embodiment of my invention shown in the accompanying drawings, in which the figure is a foreshortened side elevation, partly in section, showing my improved vapor seal mounted in a conduit near the top of a tank, the conduit being connected to foam producing equipment.

Referring more particularly to the embodiment of the invention in the drawing, numeral 5 indicates the side wall of a storage tank 4 for gasoline or other inflammable liquid, the tank having a suitable top wall 6. An opening 7 is provided near the upper portion of the side wall 5, and a suitably curved delivery conduit 8 extends from the opening into the tank to deliver foam or other fire extinguishing fluid against the side wall 5, as will be understood by those skilled in the art. Outside the tank, a T casting or conduit section 9 is secured to cover the opening 7 and is bolted to the inside delivery conduit 8 by suitable bolts 10. Gaskets 11 may be used at this joint to provide a tight seal against the escape of fumes.

The upper portion of the T conduit 9 has a vertical passageway 12 closed by a cap 13 held in place by bolts, so that the cap can be removed to inspect, adjust or replace the vapor seal. The lower end of the T conduit is partially closed by a plate 14 held in place by bolts and having a tubular member in the form of a nipple 15 threaded into a central opening in the plate. The nipple 15 may be connected by suitable couplings 16 and pipes or hoses 17 to the receiver end 18 of any suitable foam producing equipment. Since the T conduit 9 is an open communication through the delivery conduit 8 with the interior of the tank, a vapor seal is provided in the form of a plate member such as the solid disc 19 of metal or other suitable material which simply rests on the upper end of the nipple 15. If desired, the upper end of the nipple 15 may have its surface ground to provide an absolutely tight fit with the disc 19. The disc 19 is thus in a position to act as a check valve effectively preventing the escape of vapors or fumes from the tank.

The foam producing equipment shown is a device for producing what is known as mechanical or air foam and receives water under pressure from a pump, hydrant or other source through a

hose 19, the flow being regulated by a valve mechanism 20 using a control handle 21 for this purpose. The water passing through the valve flows through a flared passage 20 which leads to compartment 23 provided with a suitable nozzle or nozzles to project one or more aspirating streams of the water into the tapered receiver 18. These water jets are exposed on the outer surface to air under atmospheric pressure and thus incorporate air with the water in the receiver 18 to produce the foam. Foam stabilizing liquid or solution may be supplied through the pipe 24, controlled by the valve handle 25 and delivered either into the compartment 23 or directly into the receiver 18.

It will be apparent that any other suitable form of apparatus for producing or furnishing suitable fire extinguishing liquid under pressure can be utilized, and this apparatus may be mounted at a point adjacent the nipple 15, or may be set up at any other suitable point near the base of the tank.

In the operation of this device, the disc 19 serves as a check valve to prevent effectively the escape of vapors from the tank 4 under normal conditions. In the event of a fire, however, the first impact of foam or other fluid flowing up through the hose or pipe 17 into the nipple 15 will readily lift the disc 19 off its seat, and the disc is free to move up into the upper section 12 of the T conduit or to be carried over into the tank itself through the delivery conduit 8, which is of a substantially larger diameter than the diameter of the disc 19. In any event, the first impact of the fire extinguishing foam not only breaks the vapor seal but readily clears the passage so that the passageway is completely open for delivery of all the fire extinguishing fluid to the tank without setting up a back pressure that might present difficulties.

After the apparatus has been used, either the original seal or a new disc may be easily and quickly put in place by removing the cap 13 from the T conduit to provide access to the interior of the conduit. It is also apparent that the foam producing equipment may be left connected at all times to the T conduit, or may be disconnected at any time without interfering in any way with the proper operation of the vapor seal. This device has the outstanding advantage of being extremely simple in construction and yet highly effective as a vapor seal, and also very positive in its operation to permit the flow of foam into the tank when it is most needed. The disc 19 may be made of metal, plastic material or any other suitable breakable or non-breakable material, the weight and thickness being properly adjusted in accordance with the specific gravity of the material used to produce the most efficient operation in any given installation.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. Apparatus for supplying fire extinguishing foam to a tank comprising a foam supply conduit arranged to extend through a wall of the tank, and means in said conduit normally preventing escape of vapors from the tank through said conduit which comprises a freely movable closure

member for the conduit held in place by gravity so that it is lifted out of the way by the impact of foam passing through the conduit to the tank to permit unimpeded passage of said foam.

5 2. Apparatus for supplying fire extinguishing foam to a tank comprising a conduit arranged to extend through a wall of the tank, and a plate resting by gravity on a seat to seal said conduit completely against the flow of vapors out of the tank, said plate being free to be moved bodily 10 out of its path by the impact of a stream of foam flowing through the conduit to the tank so that the conduit is cleared and remains cleared for 15 the passage of such foam.

3. In apparatus for supplying fire extinguishing liquid to a tank, a conduit arranged to extend through a wall of the tank for the passage of said liquid, a tubular member having an opening of 20 smaller diameter and communicating with said conduit to supply said liquid thereto and having a seat formed on its upper surface, and a freely movable plate resting by gravity on said seat to close off said opening to the passage of vapors 25 from said tank.

4. In apparatus for supplying fire extinguishing air foam to a tank, a conduit arranged to extend through a wall of the tank for the passage of said foam, a substantially vertical tubular member having an opening communicating with said conduit and having a seat formed on 30 its upper surface, means for producing air foam connected to a lower portion of said member, and a check valve comprising a disc shaped plate 35 resting on said seat to close off said opening.

5. In apparatus for supplying fire extinguishing liquid to a tank, a conduit arranged to extend through a wall of the tank for the passage of said liquid, a tubular member having an opening communicating with said conduit and having a seat formed on 40 its upper surface, and a plate resting on said seat to close off said opening and held in position solely by the force of gravity, said plate being small enough to pass through said 45 conduit and being arranged to be lifted off said seat by the impact of liquid flowing through said opening.

6. In apparatus for supplying fire extinguishing air foam to a tank, a conduit arranged to 50 extend through a wall of the tank for the passage of said foam, a tubular member attached to and communicating with a lower portion of said conduit outside said tank for supplying said foam thereto, means connected to said member 55 for producing said foam, and a disc resting on the upper edge of said member to prevent the escape of vapors from the tank, said disc being free to be lifted bodily out of the way by the impact of foam flowing through said member.

7. In apparatus for supplying fire extinguishing air foam to a tank, a conduit arranged to extend through a wall of the tank for the passage of said foam, a tubular member attached to and communicating with a lower portion of said 60 conduit outside said tank, a disc resting on the upper edge of said member to prevent the escape of vapors from the tank, said conduit being larger than said disc, said disc being free to be lifted by the impact of foam flowing through said member and carried through said conduit, and means connected to said member for supplying thereto a stream of fire extinguishing air foam.

8. In apparatus for supplying fire extinguishing foam to a tank for inflammable liquids having a conduit through which the fire extinguish-

ing liquid is supplied, a seal to prevent escape of vapors from the tank through the conduit under normal conditions which comprises a valve seat in an upflow portion of the conduit, and bodily movable valve means resting by gravity on said seat, said valve means and seat being constructed and arranged so that said valve means is moved entirely out of the path of the foam by the first impact of the foam stream thereon.

9. In apparatus for supplying fire extinguishing liquid to a tank for inflammable liquids having a conduit through which the fire extinguishing liquid is supplied, a seal to prevent escape of vapors from the tank through the conduit under normal conditions which comprises a valve seat in an upflow portion of the conduit, and freely movable valve means resting by gravity on said seat, said conduit above said seat being large

enough to permit free passage of said valve means therethrough.
